UNITED STATES PATENT OFFICE.

ALFRED W. SOUTHEY, OF EDGWARE, LONDON, ENGLAND.

APPARATUS FOR THE PRODUCTION OF GASEOUS FUEL.

1,120,857.

Specification of Letters Patent.

Patented Dec. 13, 1914.

Original application filed November 12, 1912, Serial No. 730,969. Divided and this application filed December 6, 1913. Serial No. 805,048.

To all whom it may concern:

Be it known that I, ALFRED WILLIAM SOUTHEY, a subject of the King of Great Britain and Ireland, residing at Cherry 5 House, Hale Lane, Edgware, London, England, have invented new and useful Improvements in and Relating to Apparatus for the Production of Gaseous Fuel, of which the following is a specification.

10 This invention relates to apparatus for the production of gaseous fuel from liquid hydrocarbons for motive power purposes, wherein the fuel is ignited in a chamber to which air is admitted at approximately atmospheric pressure, and is a division of an 15 application heretofore filed by me, which application is serially numbered 730,969, and filed November 12, 1912.

According to the present invention I prevent 20 excessive combustion by supplying the liquid fuel to the chamber in the form of a spray of finely atomized oil, by means of which a large excess of oil or vapor is assured, so that when combustion occurs, it 25 occurs in the presence of a substantial excess of oil, which has the effect of limiting the extent of the flame of combustion and keeping the metal surfaces in the generator comparatively cool. The combustion is further effected by a highly concentrated flame 30 so as to obtain as high a temperature as possible, while at the same time the damping effect of the excess of oil prevents an over combustion of the gas which would produce 35 an excess of burnt gas.

In addition the amount of air drawn into the apparatus is regulated by the suction of the engine alone, and the liquid fuel being always largely in excess, and in a finely 40 atomized state, there is continuously formed the amount of fixed gas or gaseous fuel required by the engine. The excess of liquid fuel may be collected in the bottom of the chamber, whence it can be drawn off by the 45 pump or other means which produces the spray. As the combustion is to be regulated by the amount of air drawn in by the suction of the engine, I prefer to atomize the liquid fuel by means of a mechanical spray- 50 ing nozzle and thereby avoid using an air or steam blast, as the use of either of these would interfere with the proper regulation of combustion within the chamber.

The present invention accordingly consists 55 in a novel construction of apparatus in

which excessive combustion is prevented by the liquid fuel being supplied in the form of a spray in sufficient quantity to insure the combustion taking place in the presence of a substantial excess of oil.

The invention further consists in an apparatus in which the supply of air is regulated by the suction of the engine to form the combustible mixture with the atomized or vaporized fuel, in which mixture the atomized fuel is substantially in excess. And the invention also consists in the combination of features of the improved apparatus described below.

The accompanying drawings, by way of example, show in Figure 1, a diagrammatic view of a gaseous fuel generator for an internal combustion engine with fuel supply and circulating pump, according to this invention and in Figs. 2 and 3 respectively, 75 a sectional side elevation and plan of a generator on these lines.

In Fig. 1, *a* represents the trough of the producer connected by the passage *b* to a float chamber *c* which is in turn connected 80 to an oil reservoir *d*. Connected to the passage *b* is a duct *e* leading to a circulating pump *f* driven by the engine, which pump is connected by a pipe *g* to a spray nozzle *h* in the upper portion of the producer. A 85 short passage *i* connects the float chamber to the duct *e*. The upper portion of the generator comprises a domed cover *j* having one or more air inlets *k* in its lower edge. Within this cover is a concentrically disposed bell *l* into the upper portion of which the spray nozzle *h* opens. The lower peripheries of the cover *j* and the bell *l* are but a little distance apart leaving only a small annular passage into the generator trough 90 for air introduced by the inlets *k*. Concentrically within the bell is a coned baffle *m* on to which the center of the fuel spray is directed and the outer edge of which is lower than the edge of the bell *l*, the peripheries of the bell and the baffle forming between them an annular opening for the spray or vapor produced within the bell to pass, which opening is below the first annular opening referred to. The lower edge of 100 the baffle is some short distance above the liquid level maintained in the trough by the float. Within the baffle the gas educt *n* projects above the level of the fuel in the trough.

Referring to the details of the apparatus shown in Fig. 2, the baffle *m* may conveniently be carried upon arms *o* from the base of the educt pipe *n*. For starting, a pilot flame is obtained from a wick *d*, which is carried in a box *g* on the side of the producer, and is fed with oil from the trough *a*. The flame is drawn in through the hole *r* when the engine is started. The nozzle *h* is one of known construction, having two channels such as *t*, oppositely directed, for producing two fine jets of oil which impinge on the surrounding sleeve and are atomized. I have found it of advantage for facilitating the smooth operation of the pump which circulates the liquid, and for preventing it from knocking, to admit a minute quantity of air into the duct *e*, by means of a small pipe *u* having at the top a hole about $\frac{1}{16}$ " in diameter and extending downward below the opening *v* where the oil can flow from the float feed *c* to the duct *e*. This air has no material effect upon the spray. The pump may be a diaphragm pump worked from the tappet of the engine.

The operation of the apparatus is as follows: On the engine being started, the pump commences to deliver oil through the spraying nozzle *h*, and air is drawn in through the inlets *k*. The wick *p* (Fig. 2) is lighted and the flame drawn in through the opening *r*; this ignites the atomized fuel with which the chamber is filled, and combustion and fixation proceed, the air entering through the ports *k* to the extent required and regulated by the suction of the engine and mixing with the excess of atomized fuel from the nozzle *h*. The flame of combustion is mainly concentrated around the lower edge of the baffle *m* and is limited in extent by the small volume of air admitted relatively to the fuel and the fixed gas, vapor and products of combustion pass away to the engine by the educt *n*. The free supply of oil through the nozzle *h* keeps the baffle *m* and the interior of the chambers *j* and *l* comparatively cool. The oil as consumed is made up by the float feed from the tank *d*.

What I claim as my invention is:—

1. An apparatus for producing from liquid fuel a gaseous fuel for use with internal combustion engines, comprising an external combustion chamber, a second and smaller chamber within the external chamber and at the lower part thereof, a spraying device opening in the upper end of the outer cham-

ber for supplying liquid fuel thereinto in a finely divided state and without mixture of air, valved inlets in the lower portion of the outer chamber through which air is drawn by suction into said chamber below the fuel spraying device and burned, an outlet from the second chamber leading to the engine cylinders, and a substantially cone-shaped top for said inner chamber overlying the outlet and protecting the same from the entrance thereinto of liquid fuel.

2. In an apparatus for producing a gaseous fuel from liquid fuel for use in internal combustion engines, the combination with a combustion chamber, of a nozzle for spraying the liquid fuel into said chamber substantially free of air and in excess of the requirements to limit the excess of combustion, valved inlets through which air at normal pressure is drawn by the suction of the engine into said combustion chamber around the fuel spray, a trough for collecting excess fuel, means for producing and maintaining a concentrated flame within the combustion chamber, an outlet for the vaporized and gasified fuel, and a substantially conical baffle upon which the liquid fuel is discharged and beneath which the gaseous fuel passes to said outlet and thence to the engine.

3. In an apparatus for producing a gaseous fuel from liquid fuel for use in internal combustion engines, the combination with a combustion chamber having a cover, valved inlets in said cover through which air at normal pressure is drawn by the suction of the engine into said combustion chamber, a bell-shaped member secured to said cover and spaced a short distance therefrom at its free edge to provide an annular passage for the incoming air, an outlet for gaseous fuel leading from the combustion chamber, a baffle above and around said outlet beneath which said gaseous fuel passes to said outlet, and a nozzle extending through said cover and the bell through which liquid fuel substantially free of air is sprayed into the combustion chamber and upon said baffle to equally distribute the fuel and cause it to mix with and be partly vaporized by the entering air.

A. W. SOUTHEY.
